GILBERT W. GOODRIDGE, OF FAIRFIELD, CONNECTICUT, ASSIGNOR TO THE BRYANT ELECTRIC COMPANY, OF BRIDGEPORT, CONNECTICUT, A CORPORATION OF CONNECTICUT.

PENDENT ELECTRIC FITTING.

Application filed May 12, 1924. Serial No. 712,628.

To all whom it may concern:

Be it known that I, GILBERT W. GOODRIDGE, a citizen of the United States of America, residing at Fairfield, in the county 5 of Fairfield and State of Connecticut, have invented certain new and useful Improvements in Pendent Electric Fittings, of which the following is a specification.

My invention relates to electric fittings, 10 and particularly to a combination fitting which comprises both an attachment plug receptacle and a switch for controlling a secondary circuit. Satisfactory fittings of this type for flush installation have long 15 been in use, also more or less makeshift combinations in pendent installations, and my object is to provide a workmanlike and efficient fitting of the pendent type to replace the makeshifts heretofore commonly 20 resorted to when an installation of this character is desired.

In the accompanying drawings—

Fig. 1 is a perspective view of a fitting in which my invention is embodied in one 25 form, with an attachment plug in position to engage the receptacle contacts of the fitting;

Fig. 2 is a plan view of the base block of the fitting, with the various conductors 30 shown in position;

Fig. 3 is a similar view of the cover block of the fitting;

Fig. 4 is a view similar to Fig. 2, but showing the switch in open circuit position;

Fig. 5 is a similar view of the base block with most of the conductors removed;

Fig. 6 is a longitudinal section through the fitting drawn to a larger scale and showing the cover and base blocks as 40 assembled;

Figs. 7 and 8 are perspectives of details of the switch construction.

The body of the present fitting comprises a pair of complementary insulating blocks 45 15 and 16 of substantially the same external dimensions, meeting along a substantially medial longitudinal plane and united by screw bolts 17 which are here shown passing through and countersunk in block 16 and taking into tapped sockets 18 molded into block 15. At one end, the fitting is shaped for cooperation with an attachment plug. In view of the more or less universal use of round plug caps 19 of the blade type,

the cooperating receptacle end 20 of the fitting is here indicated as substantially circular and recessed on its end face to form guideways 21 for the cap blades. It will of course be realized, however, that the receptacle end of the fitting may be shaped to 60 any desired type of cooperating attachment plug. The body of the fitting is preferably provided with flats 22 which not only reduce the weight of the fitting, but also facilitate its grasp by the hand and properly 65 locate the fitting in the hand for ready manipulation of the switch-operating mechanism. The particular switch mechanism may also be of any appropriate type, and I have illustrated only one of various convenient 70 constructions, which may be used. The present mechanism, more fully in detail described hereinafter, is operated by a push bar, the end buttons 23 of which pass through guide channels 24 formed in the 75 adjacent faces of the blocks 15—16.

While the blocks 15 and 16 are co-extensive and to all external appearances substantially identical, the block 15 carries all the conductors of the fitting and therefore constitutes, in a way, a base block, while the block 16 forms in effect, a cover block. The block 16 is however recessed on its inner face to receive many of the conductors on the base block and thus cooperates with the latter to hold the metal parts in proper position.

Thus the blocks are recessed at one end in register to form an entrance channel 25 and diverging channels 26 and 27 for the 90 wires 28—29 and 30. The channels 26 and 27 lead respectively to binding screw terminals 31 and 32, while a third binding terminal 33, located in line with the entrance channel 25, receives the wire 30.

Extending from the wire-receiving end of the fitting to the plug receptacle end thereof, are connecting straps 34 and 35 engaged respectively at the binding terminals 31 and 32, arched intermediate their ends 100 to clear the switch mechanism, (the cover block 16 being channelled at 36 and 37 to receive the straps) and terminating in the receptacle chambers 38 and 39, where they are shaped to form, or have secured there- 105 to, receptacle contacts 40 and 41 which receive and engage the inserted blades of the plug cap 19. Direct and uninterrupted con-

nection between the wires 28, 29 and the receptacle contacts 40—41 is thus always established.

The third wire terminal 33 has associated therewith an offset switch contact 42 (Fig. 5) engaged snugly in channel 43 in base 15 and lying in a plane substantially at right angles to the plane of division between the blocks 15—16. In the same plane as the 10 contact 42 is a flange contact 44 offset from the strap 34. Both contacts enter the switch chamber 45, but lie respectively in portions of the chamber on opposite sides of the plane of division between the blocks 15 15—16.

The circuit between the thus spaced contacts is made or broken by the oscillating switch plate 46 which rides the cam 47 of the push bar 48. The latter reciprocates in 20 a plane intermediate the contacts 42—44, and at right angles to their plane. As it is displaced longitudinally, the switch plate 46, detained by its engagement with the contacts against which it rests, is bodily displaced by the cam 47 and forced to slide on the contacts until the peak of the cam passes the plane of the switch plate, whereupon the latter is thrown with a snap action by the compressed coil spring 49 away from the 30 contacts and thus breaks the switch controlled circuit. The throw of the switch plate is halted at its opposite extreme by the wall 50 of the switch chamber 45 on the one hand, and by a stop lug 51 offset 35 from the leg 52 of the frame 53. The opposite leg 54 of the frame is spaced sufficiently from the leg 52 to clear the contacts 42—44 and to permit the latter to be engaged by the switch plate without interference as it swings across the space between 40 the legs of the frame. The offsetting of the frame at 55 accommodates the spring 49 and permits it to play freely in the recess 56 in the base block 15, while the shoulder 45 57 lying in the plane of the end of the recess 56 cooperates with the latter in affording a seat for one end of the switch spring.

At the ends of the frame legs 52 and 54 are short flanges 58 which take into shallow 50 notches 59 in the base block and are located thereby in the plane of the surface 60 against which the straight edge of the bar 48 bears, and thus take the wear of said bearing. The bar is held against transverse displacement by its engagement between the frame 55 on one face and the ledges 61 depressed below the face of the base block 15. The impingement of the lugs 62 of the push bar against the stop shoulders 63, in which the ledges terminate, prevents the longitudinal 60 escape of the push bar.

While the switch frame is here shown as held in position by a screw bolt 64 taking into a tapped boss 65 in the foot piece 66 of the frame, it may be secured by a rivet

molded in the base 15, or otherwise. Tapped hollow rivets 67 molded in the base are used to secure the straps 34, 35 and 42 to the base and also to receive the several binding screws 31, 32 and 33.

70

It will be obvious to those skilled in the art that many changes in detail can be readily made, by which the same advantageous results are secured without departing from the underlying principles of the construction which I claim as my invention.

75

The utility and operation of the fitting is obvious. If the leads 28 and 29 be connected directly to the mains, current is always available at the receptacle contacts 40—41 regardless of the position of the switch. If the lead 30 be branched from the lead 29, or connected to the same main as the latter, or to the neutral of a 3-wire system, it is obvious that a device of any sort—for example a lamp socket—if arranged in the circuit 28—30, will be energized when the switch is closed. The fitting thus provides an outlet receptacle the contacts of which are always in circuit, combined with a switch which controls a circuit, portion of which is common to a portion of the receptacle circuit.

80

90

95

I claim—

1. A pendent fitting comprising a body having a longitudinally divided casing of insulating material, the parts of said casing being recessed in register on their opposed faces to form a cable entrance at one end, contact chambers at the opposite end, guideways leading to said contact chambers and a switch chamber intermediate the cable entrance and the contact chambers, together with conductors mounted on one of said casing parts and comprising a pair of wire terminals adjacent the cable entrance but on opposite sides thereof, contacts arranged in the contact chambers, connecting straps between the respective wire terminals and contacts, a third wire terminal also mounted adjacent the cable entrance, a switch contact electrically connected to said third wire terminal and projecting into the switch chamber, a commutator arranged in the switch chamber, and means associated therewith for moving the said commutator into and out of engagement with said switch contact and one of the connecting straps.

100

105

110

115

2. A pendent fitting comprising a body having a longitudinally divided casing of insulating material, the parts of said casing being recessed in register on their opposed faces to form a cable entrance at one end, contact chambers at the opposite end, guideways leading to said contact chambers and a switch chamber intermediate the cable entrance and the contact chambers, together with conductors mounted on one of said casing parts and comprising a pair of wire terminals adjacent the cable entrance but

125

130

- on opposite sides thereof, contacts arranged in the contact chambers, connecting straps between the respective wire terminals and contacts, a third wire terminal also mounted adjacent the cable entrance, a switch contact electrically connected to said third wire terminal and projecting into the switch chamber, a commutator arranged in the switch chamber and means associated therewith for moving the said commutator into and out of engagement with said switch contact and one of the connecting straps, intermediate the ends of the latter.
3. A pendent fitting comprising a body having a longitudinally divided casing of insulating material, the parts of said casing being recessed in register on their opposed faces to form a cable entrance at one end, contact chambers at the opposite end, guideways leading to said contact chambers and a switch chamber intermediate the cable entrance and the contact chambers, together with conductors mounted on one of said casing parts and comprising a pair of wire terminals adjacent the cable entrance but on opposite sides thereof, contacts arranged in the contact chambers, connecting straps between the respective wire terminals and contacts, a third wire terminal also mounted adjacent the cable entrance, a switch contact electrically connected to said third wire terminal and projecting into the switch chamber, a commutator arranged in the switch chamber, and reciprocating means associated therewith for moving the said commutator into and out of engagement with said switch contact and one of the connecting straps.
4. A pendent fitting comprising an insulating body, a pair of receptacle contacts arranged at one end of the body, a pair of wire terminals arranged at the opposite end of the body, straps extending on opposite sides of the mid plane of the body between the wire terminals and receptacle contacts to establish direct electrical connection therebetween, one of said straps having a switch contact lug offset therefrom intermediate its ends, a third wire terminal having a switch contact lug arranged in definite relation to the lug on the connecting strap, and a switch member for making and breaking connection between said switch contacts.
5. An electric switch comprising an insulating base, a frame secured to said base and lying in a plane substantially parallel to the face of the base, a reciprocating actuator confined between said frame and base and substantially parallel thereto and comprising a peaked cam, a pair of switch contacts extending in a plane at right angles to the actuator and on opposite sides of the latter, and a commutator engaging the peaked cam of the actuator, together with a spring causing said commutator to move with snap action into and out of engagement with the switch contacts on reciprocation of the actuator.
6. In an electric switch device, an insulating base, a pair of wire terminals mounted thereon, one of said wire terminals having an associated strap terminating at one end in a receptacle contact and having intermediate its ends an offset switch contact, the other of said terminals having only an associated switch contact, together with a commutator mounted on the base and adapted to make and break connection between the switch contacts.
7. In a pendent fitting, a longitudinally split casing and conductors arranged between the opposed faces of the casing parts, said casing parts being recessed to afford a cable entrance, channels for the conductors and a switch chamber, wire terminals mounted respectively on opposite sides of and in line with the cable entrance, a switch contact connected with the wire terminal mounted in line with the cable entrance, receptacle contacts mounted at the opposite end of the receptacle from the wire terminals, straps connecting the side wire terminals and receptacle contacts, a switch contact extending from one of said straps intermediate its ends into predetermined location with respect to the switch contact first mentioned and spaced therefrom, said switch contacts being arranged on opposite sides of the line of division between the parts of the insulating casing, together with a commutator adapted to make and break connection between said switch contacts.
8. In an electric fitting, a divided insulating casing, the parts of which are recessed on their opposed faces to form a switch chamber, switch contacts arranged in the said switch chamber on opposite sides of the line of division between the portions of the casing, a commutator arranged in the switch chamber and adapted to make and break connection between the switch contacts, and a reciprocating actuator engaging said commutator and having rectilinear movement through the switch casing substantially in the plane of division between the casing parts, together with a switch frame secured to one of said casing parts and extending in a direction generally parallel to the inner face thereof and serving to engage the actuator between said face of the casing and the frame.
9. In an electric fitting, a divided insulating casing, the parts of which are recessed on their opposed faces to form a switch chamber, switch contacts arranged in the said switch chamber on opposite sides of the line of division between the portions of the casing, a commutator arranged in the switch chamber and adapted to make

- and break connection between the switch contacts, and a reciprocating actuator engaging said contacts and having rectilinear movement through the switch casing substantially in the plane of division between the casing parts, together with a switch frame secured to one of said casing parts and extending in a direction generally parallel to the inner face thereof and serving to engage the actuator between said face of the casing and the frame, and a stop on the frame limiting the throw of the commutator in one direction.
10. In an electric fitting, a divided insulating casing, the parts of which are recessed on their opposed faces to form a switch chamber, switch contacts arranged in the said switch chamber on opposite sides of the line of division between the portions 20 of the casing, a commutator arranged in the switch chamber and adapted to make and break connection between the switch contacts, and a reciprocating actuator engaging said contacts and having rectilinear movement through the switch casing substantially in the plane of division between the casing parts, together with a switch frame secured to one of said casing parts and extending in a direction generally parallel to the inner face thereof and serving to engage the actuator between said face of the casing and the frame, a spring for throwing said commutator with snap action, and an abutment on the frame for one end of said spring.
15. 11. In an electric switch, a switch frame having an anchor lug at one end and a pair of spaced legs at its opposite end offset to form bearing lugs, an insulating base against which said anchor lug and bearing lugs rest, together with a reciprocating push bar having sliding engagement with said bearing lugs, and a commutator extending in a plane substantially at right angles to the actuator but moving substantially in the plane of the latter between the legs of the frame.
20. 12. In an electric switch, a switch frame having an anchor lug at one end and a pair of spaced legs at its opposite end offset to form bearing lugs, an insulating base against which said anchor lug and bearing lugs rest, together with a reciprocating push bar having sliding engagement with said bearing lugs, and a commutator extending in a plane substantially at right angles to the actuator but moving substantially in the plane of the latter between the legs of the frame, together with a switch spring engaging the commutator and extending into the space between the legs of the frame.
25. 13. In an electric switch, a switch frame having an anchor lug at one end and a pair of spaced legs at its opposite end offset to form bearing lugs, an insulating base against which said anchor lug and bearing lugs rest, together with a reciprocating push bar having

ing sliding engagement with said bearing lugs, and a commutator extending in a plane substantially at right angles to the actuator but moving substantially in the plane of the latter between the legs of the frame, together with a switch spring engaging the commutator and extending into the space between the legs of the frame, said frame being offset to accommodate the spring and to permit it to play with the commutator.

70 14. In an electric switch, a base, a sheet metal frame secured to and lying against the base, a push plate confined between the frame and base but freely slidable in a plane substantially parallel to the frame, and means for limiting the longitudinal displacement of the push plate.

75 15. In an electric switch, a base, a push plate having a sliding engagement with the base, a frame secured to the base and having spaced members bearing against the side of the push plate to confine it on the base with freedom of longitudinal displacement, a switch bar operatively engaged by the push plate and oscillating between the spaced side members of the frame.

80 16. In an electric switch, a base, a push plate having a sliding engagement with the base, a frame secured to the base and having spaced members bearing against the side of the push plate to confine it on the base with freedom of longitudinal displacement, a switch bar operatively engaged by the push plate and oscillating between the spaced side members of the frame, together 100 with a lug offset from one of the side members of the frame to limit the throw of the switch bar in one direction, and a contact overlying the other side member of the frame to limit the throw of the switch bar 105 in the opposite direction.

85 17. In an electric switch, a base recessed to form a switch chamber, contacts spaced apart in said chamber, a push plate traversing the chamber in a plane intermediate the contacts, a skeleton frame secured to the base at one side of said chamber and serving to confine the push plate between said frame and base with freedom of longitudinal movement, a switch bar actuated by the push plate and working between the sides of the switch frame to make or break the circuit between the contacts on actuation of the push plate.

90 18. In an electric switch, a switch frame comprising a sheet metal plate offset at one end to form an edge bearing for a sheet metal push bar, an offset at the opposite end of the switch frame, said frame being recessed between its side margins to permit the switch bar to play across the opening afforded by said recess.

95 19. In an electric switch, a switch mechanism comprising a sheet metal frame offset at one end, a sheet metal push plate recti- 100

linearly displaceable in a plane substantially parallel to and adjacent the switch frame, said push plate having an edge bearing against the offset at one end of the frame, 5 an offset at the opposite end of the frame, a spring seated against said offset, a push bar against which the opposite end of the spring thrusts, said switch bar being in

operative engagement with the push bar and the frame being recessed between its 10 side margins to permit play of the switch bar across the opening so formed on the actuation of the push bar.

In testimony whereof I have signed my name to this specification.

GILBERT W. GOODRIDGE.
